United States Patent Office

Des. 189,298
Patented Nov. 22, 1960

189,298

KNIFE

Lloyd F. Dowdy, Star Route, Mohawk, Oreg., and Albert E. Daughtry, 700 Wilkes Drive, Eugene, Oreg.

Filed July 30, 1959, Ser. No. 57,003

Term of patent 14 years

(Cl. D22—3)

Fig. 1 is a front elevational view of a knife showing our new design as it appears in closed position;

Fig. 2 is another front elevational view thereof as it appears in open position with the blade extended;

Fig. 3 is a side elevational view thereof;

Fig. 4 is a rear elevational view thereof;

Fig. 5 is a cross sectional view taken along the line 5—5 of Fig. 1; and

Fig. 6 is a cross sectional view taken along the line 6—6 in Fig. 2.

We claim:

The ornamental design for a knife, substantially as shown.
